UNITED STATES PATENT OFFICE.

JOHN F. KELLY, OF PITTSFIELD, MASSACHUSETTS.

SHIELD FOR CIRCUIT-CLOSERS.

1,100,485.

Specification of Letters Patent. Patented June 16, 1914.

Application filed May 31, 1912. Serial No. 700,762.

To all whom it may concern:

Be it known that I, JOHN F. KELLY, a citizen of the United States of America, residing at Pittsfield, in the county of Berkshire and State of Massachusetts, have invented new and useful Improvements in Shields for Circuit-Closers, of which the following is a specification.

This invention relates to improvements in circuit-controlling devices as used in connection with automatic piano-playing instruments, and is particularly designed as an improvement on the construction shown, described and claimed in my prior Letters Patent, dated Oct. 15, 1912, and numbered 1,041,294, in which the note-sheet, during the playing operations, travels through a tank or trough containing mercury and below a tracker bar. This bar is provided with contact terminals to cause the circuit to be closed through the mercury, by means of suitably arranged openings in the note sheet, as fully described in the above referred to Letters Patent.

25 The present invention relates to devices for closing or covering the mercury containing trough or receptacle during the threading or insertion of the note-sheet in the machine and prior to the playing operations.

The object of placing a covering device over the mercury contained in the receptacle is that many people object to placing their hands therein during the threading of the note-sheet under the tracker bar prior to the playing of a piece of music. Broadly the invention consists of a cover for the mercury receptacle operated from the tracker bar during the rising and falling of the same, the connection being such that when the tracker bar is elevated the cover is automatically moved over the receptacle and effectively prevents the person that is rethreading the circuit controller from gaining access to the mercury in the receptacle.

A further object of the invention consists in an automatic circuit-breaking device for the motor circuit in which, when the note-sheet is detached from the take-up roller at the termination of the rewinding of the note-sheet onto the let-off roller, the circuit to the motor is simultaneously broken, whereby the operation of the machine is stopped, and also at the commencement of the playing of a piece of music, as the note-

sheet is attached to the take-up roller the motor circuit is automatically closed.

Referring to the drawings, Figure 1 is an end elevation of my improvement showing the tracker bar elevated and the closer device moved over the surface of the mercury as shown in dotted lines. Fig. 2 is a sectional view taken transversely of the circuit closer, showing the tracker bar depressed in which the note-sheet is held down below the surface of the mercury, the closer plate meanwhile being withdrawn out of the path of the note-sheet. Fig. 3 is a front elevation of the winding or take-up roller showing the circuit connections within the roller which are engaged by a metallic ring or other suitable device on the end of the note-sheet so that when this ring is attached to the roller the motor circuit is closed, and, at the termination of the playing of a piece of music and the rewinding of the note-sheet onto the let-off roller *e* the circuit is broken as the device on the end of the note-sheet leaves the take-up roller. Fig. 4 is a transverse sectional view on the line 4-4 of Fig. 3 showing the ring or other device on the end of the note-sheet inserted to close the motor circuit.

Referring to the drawings in detail *a* designates the base portion of the machine to which are secured up-rights *b* and *c*. These up-rights provide bearings for the take-up roller *d* and the let-off roller *e*.

The note-sheet is indicated at *f*, the receptacle for containing mercury or other conducting fluid is shown at *g* and consists in general of the two curved portions *h* and *i* to form a receptacle or depressed portion therebetween and over which the note-sheet passes during the playing of the piece of music.

The mercury in the receptacle *g* is indicated at *j*.

k designates a standard, one located at each end of the machine and extending from one standard to the other is a tubular member *m*. Attached to this tubular member are depending arms *n*, to which arms are pivotally connected together as shown at *p*. The number of arms *n* and *o* is the same as the terminals *s*, that is to say one for each note. The arms *o* are attached to the tracker bar *q* by means of the plate of insulation *r*. Extending down through the tracker bar are the contact terminals *s* which

form an electrical connection with the arms *o* and these in turn with the depending arms *n*, which are attached to the tubular member *m* by means of the bar of insulation *t*. Extending through this bar are the terminals *u* to which the individual wires are connected that lead to the various electrical key operating devices of the musical instruments which usually consist of elec-
10 tro-magnets, all as fully shown in my prior-referred-to patent.

Referring now particularly to the mechanism by means of which the closer plate *v* is operated or moved over the surface of the mercury *j* contained in the receptacle *g* when the tracker bar *q* is elevated, *w* designates a shaft that extends longitudinally of the machine and secured to this shaft is an upwardly-extending arm *x* formed with a hook
20 *y* at its upper end that engages the pin *z* of the tracker bar *u*. This hook and pin construction is for the purpose of holding the tracker bar downward in the position shown in Fig. 2 during the playing of a piece of music. Also attached to the shaft *w* is a depending arm *4*. This arm is normally held in retracted position by means of the spring *5*; its lower portion is provided with a piece of soft iron *6* adapted to be attracted
25 by the magnet *7* when energized from the source of electrical energy by means of a suitably arranged slot or opening in the note-sheet *f* at the termination of the playing of a piece of music and prior to the re-
30 winding of the sheet onto the let-off roller *e*. When the arm *4* is attracted, the hook *y*, which is carried by the shaft *w*, is moved in the opposite direction to release the tracker bar *q* which is immediately drawn upward
35 into the position shown in Fig. 1 by means of the spring *8*, which spring is attached to the arm *9* at one end and to the pin *10* at the other. The arm *9* is rigidly connected to the links *9¹* and *9²*, the latter being attached to the tracker bar *q*. Connected to the lower end of the arm *9* at the point *11* is a rod *12* which rod is attached to the lever *13* by the pin *14*. The upper end of the lever *13* is formed with a slot *15* which receives the
40 pin *16* on the depending arm *17* of the plate *v*. It will now be seen that when the circuit is closed through the magnet *7* by means of a suitably arranged slot in the note-sheet *f* as described that, when this slot registers
45 with the proper terminal in the tracker bar *q* it will automatically be drawn upward into the position shown in Fig. 1 and cause the closer plate *v* to move into the dotted line position shown. When the plate *v* is in this
50 position the operator who rethreads the machine is thereby prevented from gaining access to the mercury in the receptacle *g*.
Referring now to the mechanism for opening the circuit to the operating motor when
55 the note-sheet *f* is released from the take-up

roller *d* at the termination of the rewinding operations. Located within this roller is a pair of rods or conducting wires *18* and *19*. These rods extend in opposite directions from the center portion of the roller *d* as shown in Fig. 3 and terminate in the contact terminals *20* and *21*.
70

22 and *23* designate brushes which are included in the motor circuit for operating the circuit closing device. It will be noticed that the inner ends of the rods or conductors *18* and *19* are placed a short distance from each other at the center of the take-up roller *d* as shown at *24* and *25* thereon. In this space is inserted the metallic ring or other device *27* which is attached to the end of the note-sheet *f*. It will be clear that when this ring is withdrawn from the space *26* at the termination of the rewinding operations that the motor circuit to the brushes *22* and *23* will be automatically opened and the motor stopped when the note sheet is unwound from the take-up roller *d*. The position of the ring *27* is clearly shown in Fig. 4 when in place. By means of this construction the circuit-closing device will be opened at the termination of the rewinding operations, thus effecting a saving in electrical energy.

What I claim is:

1. In a circuit controller device for electrically operated musical instruments, the combination, a guiding device, a note-sheet engaging said device, a conducting fluid, a receptacle for containing the fluid, a cover plate for the receptacle, connecting devices between the guiding device and the cover plates, whereby when the guiding device is elevated the conducting fluid is covered.
100

2. In a circuit controller device, the combination, a tracker bar which is adapted to be elevated and depressed, a note sheet, a receptacle for containing a conducting medium through which the note-sheet is adapted to pass when held in contact with the tracker bar, a plate or closer member adapted to be moved over the conducting medium when the bar is elevated therefrom, and connecting devices between said bar and the plate adapted to move the latter when the bar is operated and moved to an elevated position.
105
110
115

3. In a circuit controlling device for electrically operated musical instruments, a tracker bar, a note-sheet engaging the same let-off and take-up rollers to permit the note-sheet to move past the tracker bar, an electro-magnet, an electrical conducting medium through which the note-sheet is drawn during the playing of the instrument, a cover plate for the conducting medium, connections between the tracker bar and the plate, whereby when the tracker bar is elevated the closer plate is moved into a position over the conducting medium.
120
125
130
135
140

4. In a closer mechanism for electrically operated circuit closing devices, a receptacle for containing a conducting fluid, a note-sheet a tracker bar past which the note-sheet is drawn when in contact with the conducting fluid, a cover plate, means for operating said plate simultaneously with the operation of the tracker bar to cause said plate to be moved over the conducting fluid when the tracker bar is elevated.
